United States Patent Office

Des. 218,826

Patented Sept. 29, 1970

218,826

SANITARY DISPOSAL UNIT

William J. Gorman, Raytown, Mo., and John G. Markert, Overland Park, and James S. Reed, Lawrence, Kans., assignors to GMR, Inc., Lawrence, Kans., a corporation of Kansas

Filed May 5, 1969, Ser. No. 17,022

Term of patent 14 years

Int. Cl. D23—02

U.S. Cl. D23—48

Fig. 1.

Fig. 2.

Fig. 3.

FIG. 1 is a front perspective view of a sanitary disposal unit embodying our design;

FIG. 2 is a front elevational view thereof; and

FIG. 3 is a side elevational view thereof, the back and other side of the sanitary disposal unit appearing substantially similar to the side illustrated in FIG. 3.

We claim:

The ornamental design for a sanitary disposal unit, as shown and described.
